UNITED STATES PATENT OFFICE.

CHARLES H. METZ, OF WALTHAM, MASSACHUSETTS.

DESIGN FOR A BICYCLE-SHAFT.

SPECIFICATION forming part of Design No. 29,521, dated October 18, 1898.

Application filed September 2, 1898. Serial No. 690,144. Term of patent 7 years.

To all whom it may concern:

Be it known that I, CHARLES H. METZ, of Waltham, in the county of Middlesex and State of Massachusetts, have invented and produced a new and original Design for a Bicycle-Shaft, of which the following is a specification, reference being had to the accompanying drawings, forming part thereof.

In the drawings, Figure 1 represents a view in elevation of a bicycle-shaft, illustrating my new design. Fig. 2 represents a plan view of the same.

The leading feature of my new design for a bicycle-shaft consists in the frame portion extending at an angle from the cylindrical portion.

As shown in the drawings, the new design consists in the cylindrical portion 5, with the frame member 6 extending at an angle from the cylindrical portion and having the open center, and the outline which includes the projections 7 and 8 and those marked 9 9, between which is the opening 10.

What I claim is—

The design for a bicycle-shaft as herein shown and described.

CHARLES H. METZ.
